UNITED STATES PATENT OFFICE.

GEORGE A. BENDER, OF PITTSBURGH, PENNSYLVANIA.

COLLAPSIBLE SHIPPING-CASE.

1,310,777.

Specification of Letters Patent.

Patented July 22, 1919.

Application filed December 4, 1917. Serial No. 205,319.

To all whom it may concern:

Be it known that I, GEORGE A. BENDER, a citizen of the United States of America, residing at Pittsburgh, in the county of Allegheny and State of Pennsylvania, have invented certain new and useful Improvements in Collapsible Shipping-Cases, of which the following is a specification.

This invention relates to a collapsible shipping case for pianos and organs and has for its object to provide a case for such purpose, in a manner as hereinafter set forth, capable of being set up to inclose the piano or organ without employing nails for securing the elements of the case together, under such conditions preventing any possibility of damage to the article inclosed in the case to be shipped.

A further object of the invention is to provide a shipping case for the purpose set forth, in a manner as hereinafter set forth, capable of being folded when not in use, in a compact manner requiring but a small space for storage purposes.

25 A further object of the invention is to provide a collapsible case for the purpose set forth, in a manner as hereinafter referred to, whereby the entire front and top can be detached to permit the convenient removal of the piano or organ when desired.

A further object of the invention is to provide a collapsible shipping case for the purpose set forth, in a manner as hereinafter set forth, including a foldable bottom section and a series of separate elements forming the upper portion of the case, and which are capable of being nested in the bottom section and locked therein.

40 Further objects of the invention are to provide a collapsible shipping case for pianos or organs which is comparatively simple in its construction and arrangement, strong, having reinforced corners, durable, thoroughly efficient in its use, conveniently set up and readily collapsed when occasion so requires and comparatively inexpensive to manufacture.

With the foregoing and other objects in view the invention consists of the novel construction, combination and arrangement of parts, hereinafter more specifically described and illustrated in the accompanying drawings, wherein is shown an embodiment of the invention, but it is to be understood that

changes, variations and modifications can be resorted to which come within the scope of the claims hereunto appended.

In the drawings wherein like reference characters denote corresponding parts throughout the several views:

Figure 1 is a perspective view of a collapsible shipping case, in accordance with this invention, the case being set up for shipping purposes.

Fig. 2 is a perspective view of the case when collapsed, folded and nested.

Fig. 3 is a sectional front elevation of the case when collapsed, folded and nested.

Fig. 4 is a vertical sectional view of the case when set up.

Fig. 5 is a rear elevation, broken away, of the case when set up.

Fig. 6 is an elevation of one of the upper members of a side wall looking toward the inner face thereof.

Fig. 7 is a view showing both ends of the top member.

Fig. 8 is a similar view of the upper member of the front wall.

Fig. 9 is a section on line IX—IX, Fig. 4.

Fig. 10 is a rear elevation, broken away, of the brace element.

Figs. 11, 12 and 13 are sectional details.

Referring to the drawings in detail one end wall of the case is formed of a stationary member A, a hinged member B, and a detachable member C. The member B, is hinged to the member A, as at D, and is capable of folding inwardly therefrom. When the member B, is extended, it is superposed upon the member A.

The other end wall of the case is formed of a stationary member A', hinged member B' and a detachable member C'. The member B', is hinged as at E, and is capable of folding inwardly, and when extended is superposed upon the member A'.

The member C, is detachably connected to the member B, upon the top edge thereof, and the member C', is detachably connected to the member B', upon the top edge thereof. The means for connecting the member C to the member B, is similar in construction to the means for connecting the member C' to the member B', and such means consists in providing the top edge of the member B and the member B' with a pair of transversely extending grooves F, opening at the

inner faces of said members and closed at their top by slotted plates G, formed with transverse slots H of less width than the width of the grooves F. The lower edge of 5 the member C and the lower edge of the member C' are each provided with a plurality of headed studs J, adapted to engage in the grooves F and extend through the slots H, whereby the members C and C' are 10 detachably connected to the top edge of the members B and B'.

The forward edge of each of the members C and C', is beveled. Connected to the upper face, at the rear of each of the members 15 C and C', is the forward side of an angle-iron K, which overlaps the rear edge of the member, as well as extending inwardly from the said rear edge, and is provided with key-hole-shaped openings L.

20 The marginal portion of the inner face of the member C', at the top thereof, is provided with a number of bayonet shaped slots M, which open at the top edge of said member. The marginal portion of the inner 25 face of the member C', at the front thereof, is provided with a pair of bayonet-shaped slots N, which open at the front edge of said member C'. The member C', is furthermore provided in the margin thereof, at its top, 30 at the front, with an opening O.

The member C, at its top marginal portion, is provided with a pair of openings P, and at its forward marginal portion, with a pair of openings R.

35 The member B, as well as the member B', has secured to its outer face, at its rear, the forward side of an angle-iron S. The rear side of said angle-iron S, overlaps, as well as projects inwardly from the rear edge of 40 said member, and is provided with key-hole-shaped openings T. The angle-irons S, depend below the bottom edges of the members B and B' and overlap the members A and A', when the members B and B' are 45 superposed with respect to the members A and A'.

The members A and A', are fixedly secured to the bottom W, as well as being flush with the end edges of said bottom.

50 Each of the members A and A', has secured to the forward end thereof an angle-iron V, which projects forwardly from the front edge of the said members A and A'.

The rear wall of the case is formed of a 55 stationary member 1, and a pair of detachable members 2 and 3. The member 2, is detachably mounted upon the member 1, and the member 3, mounted in a similar manner on the member 2. The member 1, is of less 60 height than the members A and A', and abuts against the inner face of these latter members. The member 1, is secured to the bottom W, and also to the members A and A', by angle-irons 4, which are arranged at 65 the ends of the members 1.

Member 2, has its rear face, at each end, provided with a headed stud 4', and the member 3, has its rear face, at each end, provided with a series of headed studs 5. The studs 4' and 5, are adapted to engage in 70 keyhole-shaped openings T and L, whereby the members 2 and 3, are detachably connected to the members B, B', C, C'. The member 3, terminates at a point below the upper edges of the members C and C', and 75 forms a support or seat for the rear of the top member 6.

The top member 6, is arranged between the members C and C', and one end of said member 6, is provided with a pair of headed 80 studs 7, which engage in the slots M. That end of the member 6, provided with the studs 7, is formed with a socket 8, which is adapted to register with the opening O. A screw or other suitable means is extended 85 through the opening O and engages in the socket 8. The other end of member 6, has a pair of sockets 9, which register with the openings P. Screws 10, are extended 90 through the openings P, and engage in the sockets 9, whereby the member 6, is secured in position to close the top of the case.

The front wall of the case is formed of a bottom removable member 11, an intermediate detachable member 12, and an upper rearwardly inclined detachable member 13. The member 11, is seated against the forward edges of the members A and A', and also upon the bottom W, and the said member 11, has its ends extended between 100 the forward portion of the angle-irons V, and the forward edges of the members A and A'. Suitable screws 14, are extended through the forward portion of the angle-irons V, and engage in the member 11, for 105 securing it in position.

The member B, as well as the member B', has secured to the forward portion thereof, an angle-iron 15, which has the front portion thereof overlapping, as well as being 110 spaced from the front edge of its respective member B or B', and the said forward portion of each of the angle-irons 15, is provided with keyhole-openings 16, to receive studs 17, carried by the intermediate member 12, of the front wall.

The intermediate member 12, of the front wall, has the end portions thereof extended between the forward portion of the angle-irons 15, and the front edges of the members B and B', whereby when the studs 17, extend through the opening 16, the member 12, is detachably secured in position.

The inclined top member 13, of the front wall, has one end provided with headed 125 studs 18, which engage in bayonet slots N, of the side member C'. The other end of the top member 13, is provided with sockets 19, which register with openings R, in the side member C, whereby screws 20, can be 130

extended through said openings R, and engage in the sockets 19, and secure the member 13, in position.

The member 12, when the case is set up, is seated upon the top edge of the member 11, and the member 13, is interposed between the side members C and C', seated upon the front member 12, and has the top member 6, mounted thereon.

10 The member 1, of the rear wall is provided with lugs 21, and the bottom member 11, of the front wall with lugs 22. When the members B and B', are folded to the position shown in Fig. 2, the lugs 21, 22, 15 associate with certain of the openings 16 and T, to lock said members B and B', to the members 1 and 11, under such conditions, securing the detachable members or elements in nested position in the bottom section of 20 the case, which is formed by the said members A and A', rear member 1, front member 11, bottom W and said members B and B'.

The lugs 21 and 22, are formed by off setting portions of metallic reinforcing strips 23, 24, respectively. The strips 23, are secured to the outer face of the stationary member 1, and overlap the bottom W. The strips 24, overlap the top and bottom edges 30 of the bottom member 11 of the front wall.

Secured upon the upper face of the bottom W, are transversely extending bottom bars 25, each of which has its forward end capped by a metallic strip 26. The forward 35 end of each bar 25, has a socket 27, which registers with an opening 28, formed in the cap-strip 26. The opening 28, registers with an opening 29, formed in the member 11. The strip 24, has a countersunk opening 30, 40 for the head of a retaining screw 31, the latter being adapted to engage in the socket 27, for the purpose of detachably securing in position the member 11.

Screws may be employed, as indicated at 45 32, for detachably securing the rear of the top member 6, to the upper member 3, of the rear wall.

Angle irons 33, are employed for securing the portions A and A' to the bottom W. The angle irons 33, strengthen the ends of 50 the case at the bottoms of the side walls.

To overcome any torsional twist of the case during shipment a knock-down brace element is provided and which is arranged 55 against, as well as secured to, the inner face of the back wall. The said brace element consists of a four-way coupling 34, to each of the legs of which is connected an inclined brace member 35, which extends to a corner 60 of the case and abuts against a side wall. The bolt 36 is employed for securing the coupling 34 to the back wall. The bolt 36 extends through the coupling and also the back wall and is provided on its outer end 65 with a securing end 37. A large washer 38,

is interposed between the head of the bolt and the coupling 34.

The back wall has openings 39, which when the brace members 35, are in position register with openings 40, in said members, and the said registering openings are employed for the passage of lag-screws to engage the back of the piano to hold it in position during shipment.

Associated with the front wall is a brace 75 element 41, which is similar in construction to the brace element employed in connection with the back wall. The only difference is that the brace members of the front brace element are not provided with openings for 80 the passage of lag-screws. The front brace element is secured to the front wall in a manner similar to that in which the rear brace element is secured to the back wall.

The bottom bars are employed for supporting 85 the casters of the piano when the latter is mounted therein.

What I claim is:

1. A collapsible shipping case comprising front, rear and side walls and a bottom, each 90 of said walls consisting of a lower, intermediate and an upper member, said lower members of the side and rear walls fixedly secured to said bottom, angle-irons projecting from the forward ends of the lower 95 members of the side walls and overlapping the ends of the lower member of the front wall, means carried by and projecting from the intermediate and upper members of the side walls and overlapping and engaging 100 with the intermediate and upper members of the rear wall for detachably connecting said members together, means carried by and projecting inwardly from the intermediate members of the side walls overlapping 105 and engaging with the intermediate member of the front wall for detachably connecting said members together, means carried by said angle-irons engaging in the lower member of the front wall for detachably connecting 110 said member to the lower members of the side walls, means extending through the upper members of the side walls and engaging in the upper member of the front wall for detachably connecting said members together, a top member arranged between the upper members of the side walls, means carried by the upper members of the side walls for detachably connecting the top member therewith, and means for hinging 115 the intermediate members of the side walls to the lower members of said walls.

2. A collapsible shipping case comprising front, rear and side walls and a bottom, each of said walls consisting of a lower, intermediate and an upper member, said lower members of the side and rear walls fixedly secured to said bottom, angle-irons projecting from the forward ends of the lower 125 members of the side walls and overlapping 130

- walls overlapping an engaging with the intermediate member of the front wall for detachably connecting said members together, means carried by said angle-irons 5 engaging in the lower member of the front wall for detachably connecting said member to the lower members of the side walls, means extending through the upper members of the side walls, means extending 10 through the upper members of the side walls and engaging in the upper member of the front wall for detachably connecting said members together, a top member arranged between the upper members of the 15 side walls, means carried by the upper members of the side walls for detachably connecting the top member therewith, and means for hinging the intermediate members of the side walls to the lower members 20 of said walls, and lugs projecting from the bottom members of the front and rear walls and engaged by the connecting means carried by the intermediate members of the side walls to maintain the removable elements in nested position.
6. A collapsible shipping case comprising front, rear and side walls and a bottom, each of said walls consisting of a lower, intermediate and an upper member, said 30 lower members of the side and rear walls fixedly secured to said bottom, angle-irons projecting from the forward ends of the lower members of the side walls and overlapping the ends of the lower member of the front wall, means carried by and projecting from the intermediate and upper members of the side walls and overlapping and engaging with the intermediate and upper members of the rear wall for detachably connecting said members together, means carried by and projecting inwardly 35 from the intermediate members of the side walls overlapping and engaging with the intermediate member of the front wall for detachably connecting said members together, means carried by and projecting inwardly 40 from the intermediate members of the side walls overlapping and engaging with the intermediate member of the front wall for detachably connecting said member to the lower members of the side walls, means extending through the upper members of the side walls and engaging in the lower member of the front wall for detachably connecting said member to the lower members of the side walls, means extending through the upper members of the side walls and engaging in 45 the upper member of the front wall for detachably connecting said members together, a top member arranged between the upper members of the side walls, means carried by the upper members of the side walls for detachably connecting the top member therewith, and means for hinging the intermediate members of the side walls to the lower members of said walls, and the said upper member of the front wall being disposed at an inclination and flush with the forward edges of the top members of the side walls, and a knock-down brace element having arms abutting against the top and bottom members of the side walls, and having its central portion detachably secured to the rear wall.
8. A collapsible shipping case comprising front, rear and side walls and a bottom, each of said walls consisting of a lower, intermediate and an upper member, said lower members of the side and rear walls fixedly secured to said bottom, angle-irons projecting from the forward ends of the lower members of the side walls and overlapping the ends of the lower member of the front wall, means carried by and projecting from the intermediate and upper members of the side walls and overlapping and engaging with the intermediate and upper members of the rear wall for detachably connecting said members together, means carried by and projecting inwardly from the intermediate members of the side walls overlapping and engaging with the intermediate member of the front wall for detachably connecting said member to the lower members of the side walls, and a knock-down brace element having arms abutting against the top and bottom members of the side walls and having its central portion detachably secured to the rear wall.
7. A collapsible shipping case comprising 55 60 65 70 75 80 85 90 95 100 105 110 115 120 125 130

side walls, means extending through the upper members of the side walls and engaging in the upper member of the front wall for detachably connecting said members together, 5 a top member arranged between the upper members of the side walls, means carried by the upper members of the side walls for detachably connecting the top member therewith, and means for hinging the intermediate 10 members of the side walls to the lower members of said walls, and a knockdown brace element having arms abutting against the top and bottom members of the side walls and having its central portion detachably secured 15 to the rear wall, and a knock-down brace positioned against the inner face of the front wall, and having arms engaging the intermediate and bottom members of the side walls and having its central portion detachably secured to the front walls.

9. A collapsible shipping case comprising front, rear and side walls and a bottom, each of said walls consisting of a lower, intermediate and an upper member, said lower 25 members of the side and rear walls fixedly secured to said bottom, angle-irons projecting from the forward ends of the lower members of the side walls and overlapping the ends of the lower members of the front 30 wall, means carried by and projecting from the intermediate and upper members of the side walls and overlapping and engaging with the intermediate and upper members of the rear wall for detachably connecting 35 said members together, means carried by and projecting inwardly from the intermediate members of the side walls overlapping

and engaging with the intermediate member of the front wall for detachably connecting said members together, means carried by 40 said angle-irons and engaging in the lower member of the front wall for detachably connecting said member to the lower members of the side walls, means extending through the upper members of the side walls 45 and engaging in the upper member of the front wall for detachably connecting said members together, a top member arranged between the upper members of the side walls, means carried by the upper members 50 of the side walls for detachably connecting the top member therewith, and means for hinging the intermediate members of the side walls to the lower members of said walls, and the said upper member of the front wall being disposed at an inclination and flush with the forward edges of the top members of the side walls, and a knock-down brace element having arms abutting against the top and bottom members of the side walls, and having its central portion detachably secured to the rear walls, and a knock-down brace positioned against the inner face of the front 60 wall and having arms engaging the intermediate and bottom members of the side walls 65 and having its central portion detachably secured to the front walls.

In testimony whereof I affix my signature in the presence of two witnesses.

GEORGE A. BENDER.
